UNITED STATES PATENT OFFICE.

ANTON STEIDLE, OF ARLINGTON, MASSACHUSETTS, ASSIGNOR TO BURTON-BOSTON BRUSH CO., OF CAMBRIDGE, MASSACHUSETTS, A CORPORATION OF MASSACHUSETTS.

BRUSH.

Application filed November 23, 1925. Serial No. 70,749.

One object of my invention is to provide a brush, in which term I include a duster or similar device, which will be of very light weight, and which preferably has no wood 5 which might swell or shrink and which preferably has a short hold on the butts of the bristles so as to give the latter increased flexibility.

Other objects will be pointed out below.

10 A feature of my invention is that the butts of the bristles are inserted into a channeled holder so that the butts are firmly held in the channel, the walls of the channel being fixed with relation to each other.

15 Another feature is a particular grip for the butts which grip is parallel to the bristles.

Another feature is a unit or entity for brush making comprising a holder having a 20 plurality of channels to receive and hold bristles and a casing rigidly held to said channeled member.

Still another feature is a channel whose base is wider than its throat, the walls of the 25 throat being parallel with the bristles to give an effective grip on the bristles.

Other features will be pointed out below. In the drawing.

Figure 1 is a partial side elevation, broken 30 away in part, of a brush embodying the invention;

Figure 2 is a bottom plan view of the channeled bristle holder of the brush shown in Figure 1;

35 Figure 3 is a bottom plan view, partly broken away, of the same bristle holder, showing it secured in position in the casing;

Figure 4 is a section on line 4—4 of Figure 3;

40 Figure 5 is an end view of the channeled bristle holder;

Figure 6 is a transverse sectional view of the bristle holder;

Figure 7 is a perspective view of one of 45 the channel-closing end plates of the bristle holder shown in Figures 2 and 3;

Figures 8 and 9 illustrate two forms of bunches of bristles used in making my brush; and

50 Figure 10 is a modification described below.

The member 1 for holding the bristles is made preferably of sheet metal bent to the form shown clearly in Figures 4 and 6 to

form channels or grooves 2 for the reception 55 of the bristles, the channels being wider at the bottom 3 than at the throat 4 so that when the ends of the butts spread they are held within the channel against pulling out through the throat. I prefer to make the 60 walls 5 of the throat parallel with the bristles to give a very firm grip on the bristles with the result that the body of the bristles may be very flexible and yet the bristles are very firmly held. To each end of the 65 holder member 1 I solder members 6 to close the ends of the two inner channels 2.

The holder is fastened rigidly to casing 7 by means of tubular rivets 8 passing through perforations 21 in the holder and similar 70 perforations in the casing. Tubular spacing washers 9 surround the shanks of the rivets and hold the casing 7 and the portions 19 of the holder in proper spaced relation, said rivets and spacing washers being located between the channels so as not to interfere with the bristles in the channels. The holder is preferably shorter than the casing 75 so as to provide end channels or grooves 10.

The casing 7 and holder 1 are held to the 80 handle 11 by screws 12 passing through the tubular rivets 8.

The bristles 13 are shown in Figure 9 as cemented together at their butts to form a long and relatively narrow bunch or tuft 85 while in Figure 8 a similar shorter bunch is shown, these bunches being inserted in the holder in a manner more fully described below.

In Figure 10 I illustrate another form of 90 sheet metal holder 14, in which the walls 15 are substantially straight, the butts of the bristles being gripped in the channels 16 as in the other form.

In assembling the bristles in my brush 95 thin rubber cement is preferably placed in the grooves.

A suitable long and relatively narrow bunch or tuft of bristles is assembled and dipped in a heavy solution of rubber cement, 100 the bunch being about half the length of one of the long grooves and being a little thicker than the opening of the throat and having its butts pressed together by a vise or otherwise. The butts of the bristles of 105 the bunch are then inserted into, and against the base of, a groove or channel whereupon the butts spread apart. I then press, with

a knife or other suitable tool, against one end of the bunch and then against the other, forcing the bunch very compactly together longitudinally, this pressing and forcing tending to spread apart the ends of the bristles within the groove and transversely thereof with the result that said ends hold with great firmness with a short hold within the groove, thereby providing great flexibility for the bristles in use, the cement, after vulcanization, adding to such holding. I prefer to first insert a bunch of bristles about half the length of the groove, as shown in Figure 9, and after this has been 10 pressed together I insert a similar bunch and when this has been pressed together I may insert smaller bunches, such as that shown in Figure 8, to completely fill the groove longitudinally. Bunches are similarly inserted in all the grooves and in the grooves between the plate 6 and the ferrule. Vulcanizing is then had and during it the cement in said spaces is pressed above the 20 casing and firmly binds the bristles to the casing, the bottom of the casing being preferably slightly below the bottom of the holder and curving slightly at 16° inwardly to grip the bristles, the member 6 being bent as shown in Figure 1 so that the channel between the casing and holder is wider at the base than at the throat.

What I claim is:

1. A brush comprising a casing; a channeled bristle carrying holder arranged within the casing; eyelet rivets connecting the casing and holder; and spacing washers surrounding the rivets between the casing and holder.
2. A brush comprising a handle; a casing; a bristle carrying holder arranged within the casing; tubular rivets fastening the casing and holder together in fixed relation; and screws extending through said tubular rivets into said handle.
3. A brush comprising a casing; a bristle holder within the casing and having a plurality of channels in which the bristles are anchored; eyelet rivets connecting the casing and holder; and spacing washers surrounding the rivets between the casing and holder, said washers and rivets being disposed between said channels.

4. In a brush, a bristle carrying holder, a casing spaced from the holder, bristles secured in said space, said casing having a portion extending below the bottom of the holder and gripping the bristles in said space.

5. The combination of a bristle holder having a plurality of channels to receive bristles within them, said channels being fixedly spaced apart with relation to each other and each having a base and two side walls; a casing within which said holder is arranged; and means to hold the holder and casing rigidly together.

6. The combination of a bristle holder made of sheet metal and having a plurality of channels to receive bristles within them, each channel having a base and two side walls; a metal casing within which said holder is arranged; and means to hold the holder and casing rigidly together.

7. A brush comprising a casing; a bristle carrying holder arranged within the casing and having a plurality of channels, each channel having a base and two side walls; said holder also comprising a portion connecting adjacent channels and spacing them from each other transversely of the brush, said portion being spaced from the casing; means to hold said portion spaced from the casing; and means to hold the casing and holder together.

8. A brush comprising a channeled holder, the walls of the channel being fixed relatively to each other; bristles having their butts seated in the channel; means closing the ends of the channel to confine the butts in the channel; a casing within which the holder is arranged, the ends of the casing being spaced from said closing means, and bristles secured in the space between the holder and the casing.

9. In a brush, a channeled holder; bristles having their butts seated in the channel; means closing the ends of the channel to confine the butts in the channel; a casing within which the holder is arranged, the ends of the casing being spaced from said closing means; and bristles secured in the space between the holder and the casing.

ANTON STEIDLE.
